WELL TOOL AND METHOD OF USING SAME
Rufus P. Kirk, Odessa, Tex.
(1417 Sherwood Lane, Oklahoma City, Okla.)
Filed May 3, 1962, Ser. No. 192,120
15 Claims. (Cl. 166—44)

This invention relates to new and useful improvements in well tools and methods of using same.

An object of this invention is to provide a new and improved valve for a well pipe which is open to provide for the unloading of mud or other fluid in the pipe and which is automatically closed to provide for the flow of the oil or other well fluid after the unloading.

An important object of this invention is to provide a new and improved method for displacing fluid in a casing annulus and well tubing by circulating a gas or a liquid lighter than the fluid to be displaced, then closing off such circulation, and producing oil or other well fluid through the tubing.

Another object of this invention is to provide a new and improved method and valve which is adapted to be used in conjunction with one or more gas lift valves for improving the operation of the gas lift valves by providing a lower liquid level in the casing annulus than is normally attained in the absence of such valve.

A particular object of this invention is to provide a new and improved valve adapted to be positioned in a well tubing longitudinally below a lateral opening in the tubing, said valve having a frangible closure which is adapted to be fractured upon an upward movement of the valve in the tubing, whereby the valve closes off the flow through said lateral opening and opens flow from said tubing through said valve.

A further object of this invention is to provide a new and improved method and apparatus wherein circulation between a casing annulus and an opening in a well tubing is effected, then such circulation is stopped by closing such opening, and thereafter such opening is opened again by a well tool to permit a killing of the well, further circulation, or similar operations.

The preferred embodiment of this invention will be described hereinafter, together with other features thereof, and additional objects will become evident from such description.

The invention will be more readily understood from a reading of the following specification and by reference to the accompanying drawings forming a part thereof, wherein an example of the invention is shown, and wherein:

FIG. 1 is a schematic view illustrating the first part of the method of this invention wherein the gas is being introduced into the casing annulus for displacing the mud in the annulus and the tubing;

FIG. 2 is a view similar to FIG. 1, but showing a further step in the method of this invention wherein substantially all of the mud in the casing annulus and tubing have been displaced by the gas;

FIG. 3 is a view similar to FIG. 1 and FIG. 2, but illustrating the valve of this invention in a closed position for closing off the lateral opening between the tubing and the casing annulus and the subsequent production of oil or well fluid through the tubing to the surface;

FIG. 4 is a schematic view illustrating a modified form of the method of this invention wherein gas lift valves are employed, and wherein a first stage of such method is illustrated with the gas injected into the casing annulus and operating the upper gas lift valve;

FIG. 5 is a view similar to FIG. 4, but illustrating the modified form of the invention of FIG. 4 wherein the next phase is indicated by the displacement of the drilling

2

mud or other fluid in the annulus and tubing with gas injected from the surface;

FIG. 6 is a view similar to FIGS. 4 and 5 and illustrates the next phase of the method of such modified form of the invention, wherein the lateral opening in the well pipe or tubing is closed by the valve and the gas lift operations are performed by the predetermined gas pressure in the casing annulus which is introduced through the gas lift valves;

10 FIG. 7 is a vertical sectional view of the preferred form of the valve of this invention, shown in the position for closing off flow through the valve body while permitting flow through the lateral opening of the well pipe or tubing; and

15 FIG. 8 is a view similar to FIG. 7, but illustrating the valve in the position closing the lateral port of the well pipe or tubing and providing an opening through the valve body for the flow of oil or other well fluid upwardly through the valve body and into the tubing or pipe there-

20 above.

In the drawings, the letter C designates a well casing which is of conventional construction and which has a well pipe or tubing T therein, with a casing annulus A therebetween. The well pipe or tubing T has a lateral

25 opening or openings 10 formed therein, the opening and closing of which is controlled by a valve V, the details of which will be explained hereinafter. A packer P of conventional construction is disposed in the casing annulus A below the opening or openings 10. Briefly, in carrying out the method of this invention using the valve V of this invention, gas or other fluid G is introduced into the upper end of the casing C so as to force the drilling mud M or other well fluid downwardly in the annulus A, through the opening or openings 10 and upwardly in the well pipe

30 or tubing T. Such circulation of the gas G continues until a pressure differential is developed across the valve V within the tubing T which is sufficient to move the valve V automatically to a closed position (FIG. 3). When the valve V is in the closed position, the well fluid W, generally oil, is produced through the pipe or tubing T for discharge at the surface S, or through any other suitable well head equipment. Also, as will be explained in connection with FIGS. 4-6, the method of this invention

35 may be employed in conjunction with gas lift valves on the well pipe or tubing T. Furthermore, if it is necessary or desirable to open the valve V again after it has been moved to the closed position, such opening can be accomplished by the use of a wire line tool so that the well can be killed with mud or the like, or other similar well operations performed.

Considering now the details of the valve V of this invention, which are shown in FIGS. 7 and 8, such valve V includes a tubular pipe section 12 having the openings 10 formed laterally therethrough. Such section 12 has an adapter 14 threaded or otherwise secured to its upper end and a second adapter 15 threaded or otherwise connected to its lower end. The adapter 14 is connected to a pipe section 16 which extends upwardly with the rest of the pipe or tubing T to the surface S. The adapter 15 connects with a tubing section 17 by means of threads or any other suitable connecting means so that the tubing string T continues on down below the valve V.

The valve V includes a longitudinally movable valve body 20 which has an upper bore 20a and a lower bore 20b. The bores 20a and 20b are of the same internal diameter and it is to be noted that the thickness of the valve body 20 extending from such bores 20a and 20b outwardly, together with the thickness of the valve section 12, are approximately the same as the thicknesses of the adapters 14 and 15 and the normal tubing sections 16 and 17. Therefore, the valve V of this invention provides a

full open bore, as will be more fully explained, without enlarging the external diameter of the tubing string T. In circumstances where the enlargement of the tubing string at the valve V is not undesirable, the thicknesses of the valve section 12 and the body 20 may be increased.

The valve body 20 has a lower annular extension 20c which fits into an annular slot 15a at the upper end of the adapter 15. Suitable shear pins 25 extend through the downwardly extending flange 20c and the upper portion of the adapter 15 to securely hold the valve body 20 in its lower position wherein the openings 10 are open for fluid flow therethrough. Such pins 25 are adapted to be severed or sheared upon the application of a predetermined fluid pressure differential acting across the valve body 20, as will be more evident hereinafter. Suitable external seal rings 26 at the lower end and 27 at the upper end are provided for sealing on both the upper and lower sides of the openings 10 when the valve body 20 is in the position for closing such openings 10 (FIG. 8).

The body 20 is provided with an annular external recess 20d above the O-rings 27, which recess 20d receives a split metallic lock ring 30. Such ring 30 is confined in a compressed condition when the valve body 20 is in the lower position shown in FIG. 7, but is expanded by its own resilience to the position shown in FIG. 8 when the valve body 20 has moved upwardly to close the openings or ports 10. Such lock ring 30 retains the valve body 20 in the upper position of FIG. 8 even after the well fluid pressure differential has ceased to act in an upward direction on the body 20. A seal ring 28 which is also of rubber and preferably an O-ring, is located above the lock ring 30 to reduce the amount of corrosive fluids which might otherwise reach the lock ring 30.

The valve body 20 has an annular lateral shoulder 20e formed above the bore 20a for receiving a closure disk 31. The peripheral edges of the disk 31 are in contact with an annular seal ring 32 formed of rubber or other similar resilient material so as to prevent or inhibit fluid flow or leakage around the closure disk 31. A resilient metal snap ring 34 is positioned above the closure disk or plate 31 to hold such disk or plate 31 in position on the valve body 20 as shown in FIG. 7. The closure disk or plate 31 may be made of any suitable frangible material such as tempered glass or ceramic material. The material must be sufficiently strong to withstand the pressure differential acting thereacross, but at the same time it must shatter to small pieces when fractured to open flow through the valve body 20, as will be more fully explained.

In order to provide for the movement of the valve body 20 downwardly from the position closing the ports 10 as shown in FIG. 8 to the position opening the ports 10 as shown in FIG. 7, it is desirable to provide a central bore section 20f of an increased internal diameter as compared to the bore sections 20a and 20b. Such enlarged bore section 20f provides for a lower lateral shoulder 20g which is adapted to be contacted by a conventional wire line operated well tool shown in dotted lines and indicated by the letter R in FIG. 8.

The valve section 12 is formed with an enlarged internal diameter section 12a at its upper end so that the split expandable ring 30 may expand outwardly as shown in FIG. 8 to hold or lock the sleeve 20 in the upper position.

The adapter 14 has a plurality of sharp pointed projections 14a which are adapted to contact the closure disk or plate 31 as the valve body or sleeve 20 moves upwardly by the action of the fluid pressure differential within the well. Such projections 14a cause a fracturing of the fragile material forming the disk or plate 31, whereby such disk or plate 31 breaks into very small pieces which then fall downwardly into the well, or are carried out with the well fluid as it flows upwardly through the tubing T to the surface S. It will be appreciated that after the closure disk 31 has been fractured and removed, then the full bore of the valve body or sleeve 20 is open

for the flow of fluid through the valve body or sleeve 20 to the upper portion of the tubing T. The lock ring 30 expands to the position shown in FIG. 8 within the enlarged diameter 12a to hold or lock the body or sleeve 20 in the upper position, by the frictional engagement with the internal surface of the bore 12a, and also by a contact with the inclined annular surface 12b formed below the bore 12a. The fragments of the closure disk 31 are indicated by the designation 31a in FIG. 8 to indicate that such fragments 31a are moving with the well fluid.

It should be pointed out that the upper surface 31b (FIG. 7) of the disk 31 is preferably coated with a layer of rubber or similar material which will resist abrasion or sandblasting action caused by the circulation of mud or other fluid prior to the breaking of the disk 31. A similar coating 31c may also be provided on the lower surface of the disk 31, although it generally is not as desirable or necessary.

In carrying out the method of this invention as particularly illustrated in FIGS. 1-3, the tubing T is initially positioned in the casing C with the packer P in position as shown in FIG. 1. The valve V is lowered with the tubing string T and is secured in its lower position (FIG. 7) by means of the shear pins 25. The shear pins 25 are set at the time of assembly so as to shear or sever at a predetermined fluid pressure differential acting across the body 20 and the closure plate 31.

The pins 25 are of such strength that the pressure of the oil or other well fluid W below the valve V, minus the pressure of the gas G introduced into the casing annulus A will sever or shear such pins 25. In order to provide some flexibility in the amount of force necessary to shear the pins 25, they can be made so that they will shear at the pressure of the oil or well fluid W. Then, if the gas pressure G is too high so that the pressure differential between the well fluid and the gas is not sufficient to sever the pins 25, the gas pressure can be bled off to as low as atmospheric pressure in order to create an adequate pressure differential across the body 20 and the closure 31.

In any event, after the tubing T has been positioned as shown in FIG. 1 with the packer P below the lateral openings 10, the gas G or other fluid lighter in density than the mud M is introduced at the upper end of the annulus A through any suitable well head equipment schematically indicated at C'. Such gas G displaces the mud downwardly in the annulus A through the lateral openings 10 and then upwardly in the tubing T for discharge through the surface outlet S. Since the mud is of a greater density than the gas or other fluid G, the pressure differential acting across the valve body 20 and the closure plate 31 is smaller with the mud than with the gas. Preferably, the gas G fully displaces the mud M, or at least the gas G reaches the level G' or one similar thereto as shown in FIG. 2 before the pins 25 shear. Such pins 25 shear automatically when the pressure differential acting across the valve body 20 is sufficient to sever the pins 25. The valve body 20 is then moved upwardly by the pressure differential so that the closure plate or disk 31 hits the projections 14a with a blow or impact sufficient to crack or shatter the material of the plate or disk 31 into small particles 31a (FIG. 8). The well fluid is thus capable of flowing upwardly through the bore of the body 20 into the tubing T thereabove. In the usual case, the particles 31a are carried upwardly with the well fluid and are discharged at the upper surface outlet S.

When the valve body 20 has moved upwardly to the closed position, the seal rings 26 and 27 span the openings 10. The gas G is thus confined in the annulus A, and preferably the inlet line C' is closed with a valve or other suitable means X (FIG. 3).

Thus, with the method of this invention as described above and as illustrated in FIGS. 1-3, the mud or other well fluid is displaced from the annulus and the tubing

after the packer P is set, causing the well to flow with the oil or other well fluid without the use of swabbing or wire line operations inside the tubing. Also, the dangers inherent in unloading a well before setting the packer are eliminated with this invention.

The gas G is preferably nitrogen or methane, but other gases may be used. Also, a light density fluid such as water, which has a lighter density than the usual mud M in the well, may be used in place of the gas G. So long as the gas or other fluid G has a light enough density to cause a sufficient unloading of the mud M to reduce the pressure above the valve V so as to develop a pressure differential across the valve V sufficient to sever the shear pins 25, it will suffice for the purpose of this invention.

In the form of the invention shown in FIGS. 4-6, gas 15 is used as the primary unloading fluid since gas lift valves indicated schematically at F-1, F-2 and F-3 are preferably used with such form of the invention. It will be understood that although only three gas lift valves are illustrated in FIGS. 4-6, additional valves may be employed, depending upon the usual spacing and production requirements. Even though the gas lift valves are employed in the modified form of the invention shown in FIGS. 4-6, the method as described in connection with FIGS. 1-3, and the operation of the valve V are basically the same. Thus, the gas G or other fluid which is lighter than the mud M is introduced at the well head connection C' to the annulus A for unloading or displacing the mud M from the annulus A and the tubing T. The valve V is in the lower position wherein the ports 10 are opened during such circulating or unloading of the mud M from the tubing T. During such unloading, the gas lift valves may function to introduce or inject gas into the tubing T before the level of the gas G has reached the lateral openings or ports 10, but such action of the gas lift valves is not necessary until after the gas G has completely unloaded the annulus A and has at least partially unloaded the tubing T.

When the pressure differential acting across the valve body 20 and the closure disk or plate 31 reaches the predetermined value necessary to shear the pins 25, the valve body 20 moves upwardly to the position shown in FIG. 8 and closes the ports 10.

With the valve V in the closed position, closing the ports 10 and with the disk 31 shattered to allow the well fluid W to flow upwardly through the body 20 and into the tubing T, the usual production techniques with the gas lift valves are then employed. However, the gas lift valves operate more satisfactorily with the present method and apparatus because the presence of the gas at the point below the lowest of the gas lift valves is assured with the present invention. The present method, when used in conjunction with the gas lift valves, makes it possible to work the lowest gas lift valve which is set to open at the gas pressure in the annulus A, and minimizes problems in gas lift production such as improper valve spacing, emulsion formation, and differentials in liquid levels in the tubing and annulus. The pressure of the gas G in the annulus A is maintained for continuous flow lifting or controlled for intermittent or slug lifting through the inlet valve X or other suitable means so that the gas injection into the tubing T is thereby controlled after the valve V has moved to the position shown in FIG. 6.

Other advantages in addition to those enumerated above will occur to those skilled in the art in connection with the use of the present invention in conjunction with the gas lift valves as shown in FIGS. 4-6. It will also be appreciated that this invention may be used in dual production lines.

The foregoing disclosure and description of the invention is illustrative and explanatory thereof and various changes in the size, shape and materials, as well as in the details of the illustrated construction, may be made within the scope of the appended claims without departing from the spirit of the invention.

What is claimed is:

1. A valve adapted to be mounted in a well pipe having a lateral opening therethrough, comprising:
  - (a) a tubular valve body mounted in said well pipe for longitudinal movement relative to said pipe,
  - (b) closure means carried by said body for closing off fluid flow from said pipe through said valve body,
  - (c) retaining means releasably retaining said valve body in an open position in said pipe permitting fluid flow through said lateral opening,
  - (d) said retaining means being releasable upon the application of a predetermined fluid pressure differential acting on said closure means for moving said body longitudinally in said pipe to close said lateral opening, and
  - (e) opening means for engaging said closure means upon the longitudinal movement of said valve body for opening said closure means and permitting flow through said body from said pipe.
2. The structure set forth in claim 1, wherein
  - (a) said closure means is frangible into relatively small pieces, and
  - (b) said opening means for engaging said closure means includes means for fracturing said closure means upon the longitudinal movement of said valve body relative to said pipe.
3. A valve adapted to be mounted in a well pipe having a lateral opening therethrough, comprising:
  - (a) a tubular valve body mounted in said well pipe for longitudinal movement relative to said pipe,
  - (b) closure means carried by said body for closing off fluid flow from said pipe through said valve body,
  - (c) retaining means releasably retaining said valve body in a position permitting fluid flow through said lateral opening,
  - (d) said retaining means being releasable upon the application of a predetermined fluid pressure differential acting on said closure means of said valve body for moving said body longitudinally in said pipe to close said lateral opening, and
  - (e) means for opening said closure means upon the longitudinal movement of the valve body for permitting fluid flow in the well pipe.
4. The structure set forth in claim 1, wherein said retaining means is a shear pin connecting said valve body to said pipe and adapted to shear when said predetermined fluid pressure differential is developed.
5. The structure set forth in claim 3, wherein said retaining means is a shear pin connecting said valve body to said pipe and adapted to shear when said predetermined fluid pressure differential is developed.
6. The structure set forth in claim 3, including
  - seal means between said valve body and said well pipe for inhibiting fluid flow downwardly around said valve body when said valve body is in said open position, whereby fluid may be circulated between the interior and exterior of said pipe through said lateral opening above said seal means and said closure means.
7. In combination with a well pipe in a well casing wherein the annulus between the casing and the pipe is packed off with a packer, and wherein the pipe has a lateral opening therethrough above the packer, the improvement residing in a valve, comprising:
  - (a) a tubular valve body mounted in said well pipe for longitudinal movement relative to said pipe,
  - (b) closure means carried by said body for closing off fluid flow from said pipe through said valve body,
  - (c) retaining means releasably retaining said valve body in a position permitting fluid flow through said lateral opening,
  - (d) said retaining means being releasable upon the application of a predetermined fluid pressure differential acting on said closure means of said valve body

- for moving said body longitudinally in said pipe to close said lateral opening, and
- (e) means for opening said closure means upon the longitudinal movement of the valve body for permitting fluid flow in the well pipe.
8. In combination with a well pipe in a well casing wherein the annulus between the casing and the pipe is packed off with a packer, and wherein the pipe has a lateral opening therethrough above the packer, the improvement residing in a valve, comprising:
- (a) a tubular valve body mounted in said well pipe for longitudinal movement relative to said pipe,
- (b) closure means carried by said body for closing off fluid flow from said pipe through said valve body,
- (c) retaining means releasably retaining said valve body in an open position in said pipe permitting fluid flow through said lateral opening,
- (d) said retaining means being releasable upon the application of a predetermined fluid pressure differential acting on said closure means for moving said body longitudinally in said pipe to close said lateral opening, and
- (e) opening means for engaging said closure means upon the longitudinal movement of said valve body for opening said closure means and permitting flow through said body from said pipe.
9. A method of producing well fluid through a tubing in a well casing, wherein the annulus between the tubing and the casing is packed off with a packer and wherein the tubing has a lateral opening above the packer, comprising the steps of:
- (a) closing off fluid flow downwardly through the tubing below the lateral opening,
- (b) circulating a fluid down the casing annulus and through said lateral opening for flow upwardly in said tubing to thereby displace the fluid previously in the annulus and tubing with a lighter density fluid,
- (c) developing a predetermined fluid pressure differential across the closed off portion of the tubing sufficient to effect an opening of the tubing, and
- (d) closing said lateral opening in response to said fluid pressure differential to discontinue circulation from the annulus to the tubing while enabling well fluid to be produced through the tubing.
10. In combination with a well pipe in a well casing wherein the annulus between the casing and the pipe is packed off with a packer, wherein a plurality of longitudinally spaced gas lift valves are mounted on the well pipe in the annulus, and wherein the pipe has a lateral opening at a point below said gas lift valves and above the packer, the improvement residing in a valve, comprising:
- (a) a tubular valve body mounted in said well pipe for longitudinal movement relative to said pipe,
- (b) closure means carried by said body for closing off fluid flow from said pipe through said valve body,
- (c) retaining means releasably retaining said valve body in a position permitting fluid flow through said lateral opening,
- (d) said retaining means being releasable upon the application of a predetermined fluid pressure differential acting on said closure means of said valve body for moving said body longitudinally in said pipe to close said lateral opening, and
- (e) means for opening said closure means upon the longitudinal movement of the valve body for permitting fluid flow in the well pipe.
11. In combination with a well pipe in a well casing wherein the annulus between the casing and the pipe is packed off with a packer, wherein a plurality of longitudinally spaced gas lift valves are mounted on the well pipe in the annulus, and wherein the pipe has a lateral opening at a point below said gas lift valves and above said packer, the improvement residing in a valve, comprising:
- 5
- 10
- 15
- 20
- 25
- 30
- 35
- 40
- 45
- 50
- 55
- 60
- 65
- 70
- 75
- 8
- (a) a tubular valve body mounted in said wall pipe for longitudinal movement relative to said pipe,
- (b) closure means carried by said body for closing off fluid flow from said pipe through said valve body,
- (c) retaining means releasably retaining said valve body in an open position in said pipe permitting fluid flow through said lateral opening,
- (d) said retaining means being releasable upon the application of a predetermined fluid pressure differential acting on said closure means for moving said body longitudinally in said pipe to close said lateral opening, and
- (e) opening means for engaging said closure means upon the longitudinal movement of said valve body for opening said closure means and permitting flow through said body from said pipe.
12. A method of producing well fluid through a tubing in a well casing, wherein the annulus between the tubing and the casing is packed off with a packer, wherein a plurality of longitudinally spaced gas lift valves are mounted on the well pipe in the annulus, and wherein the pipe has a lateral opening below said gas lift valves and above the packer, comprising the steps of:
- (a) closing off fluid flow downwardly through the tubing below the lateral opening,
- (b) circulating a gas down the casing annulus and through said lateral opening for flow upwardly in said tubing to thereby displace the gas previously in the annulus and tubing with a lighter density gas,
- (c) developing a predetermined fluid pressure differential across the closed off portion of the tubing sufficient to effect an opening of the tubing,
- (d) thereafter closing said lateral opening in said tubing to discontinue the circulation from the annulus to the tubing, and
- (e) then producing oil through said tubing.
13. A method of producing well fluid through a tubing in a well casing, wherein the annulus between the tubing and the casing is packed off with a packer, wherein a plurality of longitudinally spaced gas lift valves are mounted on the well pipe in the annulus, and wherein the pipe has a lateral opening below said gas lift valves and above the packer, comprising the steps of:
- (a) closing off fluid flow downwardly through the tubing below the lateral opening,
- (b) circulating a gas down the casing annulus and through said lateral opening for flow upwardly in said tubing to thereby displace the gas previously in the annulus and tubing with a lighter density gas,
- (c) developing a predetermined fluid pressure differential across the closed off portion of the tubing sufficient to effect an opening of the tubing,
- (d) thereafter closing said lateral opening in said tubing to discontinue the circulation from the annulus to the tubing, and
- (e) then producing oil through said tubing while controlling the gas pressure in said annulus for gas injection into said well pipe through said gas lift valves to effect a gas lift of the oil.
14. A valve adapted to be mounted in a well pipe having a lateral opening therethrough, comprising:
- (a) a tubular valve body mounted in said well pipe for longitudinal movement relative to said pipe,
- (b) closure means carried by said body for closing off fluid flow from said pipe through said valve body,
- (c) retaining means releasably retaining said valve body in a position permitting fluid flow through said lateral opening,
- (d) said retaining means being releasable upon the application of a predetermined fluid pressure differential acting on said closure means of said valve body for moving said body longitudinally in said pipe to close said lateral opening,
- (e) means on said body engageable by a tool lowered

in said pipe for effecting a longitudinal movement of said body to open said lateral opening, and (f) means for opening said closure means upon the longitudinal movement of the valve body for permitting fluid flow in the well pipe.

15. A method of producing well fluid through a tubing in a well casing, wherein the annulus between the tubing and the casing is picked off with a packer and wherein the tubing has a lateral opening above the packer, comprising the steps of:

- (a) closing off fluid flow downwardly through the tubing below the lateral opening,
- (b) circulating a fluid down the casing annulus and through said lateral opening for flow upwardly in said tubing to thereby displace the fluid previously in the annulus and tubing with a lighter density fluid,
- (c) developing a predetermined fluid pressure differential across the closed off portion of the tubing sufficient to effect an opening of the tubing,
- (d) thereafter closing said lateral opening in said tubing to discontinue the circulation from the annulus to the tubing,

5

10

15

20

(e) then producing well fluid through said tubing, and (f) subsequently again opening said lateral opening for killing the well and similar operations.
